UNITED STATES PATENT OFFICE.

GUSTAVE STICKLEY, OF SYRACUSE, NEW YORK.

DESIGN FOR A SCREW.

SPECIFICATION forming part of Design No. 35,710, dated February 11, 1902.

Application filed October 28, 1901. Serial No. 80,339. Term of patent 14 years.

To all whom it may concern:

Be it known that I, GUSTAVE STICKLEY, a citizen of the United States, residing at Syracuse, county of Onondaga, State of New York, 5 have invented and produced a new and original Design for Screws, of which the following is a specification, reference being had to the accompanying drawings.

Figure 1 is a top plan view showing the 10 head of the screw. Fig. 2 is a side or edge elevation of the screw complete. Fig. 3 is a corner view thereof.

As shown in the drawings, the leading or 15 material feature of my design comprises a screw-body having a rectangular-shaped head when viewed from the top, the sides being of substantially equal length, and cone-shaped when viewed from the side, having its edges 20 in a vertical plane and terminating at the top in angular facets.

a is the body, and *b* the angular head, said head having its edges extending in a vertical plane and the major part of the top in the form of triangular facets terminating in a cress, the upper plane of which is substantially parallel with the bottom, as shown, the whole forming a unitary article of manufacture.

Having thus described my invention, what I claim, and desire to secure by Letters Patent, is—

The design for a screw as herein described and shown.

In witness whereof I have hereunto set my hand this 18th day of October, 1901.

GUSTAVE STICKLEY.
